UNITED STATES PATENT OFFICE.

JAMES F. SMITH, OF ST. LOUIS, MISSOURI, ASSIGNOR OF ONE-THIRD TO ANTHONY F. ITTNER AND ONE-THIRD TO ARTHUR H. BRADLEY, BOTH OF ST. LOUIS, MISSOURI.

TONE-ARM FOR TALKING-MACHINES.

1,302,478.

Specification of Letters Patent. Patented Apr. 29, 1919.

Original application filed June 22, 1916, Serial No. 105,141. Divided and this application filed August 24, 1917. Serial No. 187,921.

To all whom it may concern:

Be it known that I, JAMES F. SMITH, a citizen of the United States, and a resident of the city of St. Louis and State of Missouri, have invented a new and useful Improvement in Tone-Arms for Talking-Machines, of which the following is a specification.

This invention relates to tone arms for talking machines and particularly to tone arms used in connection with sound boxes of the type shown in my pending application Serial No. 105,141, filed June 22, 1916. The present application is a division of said application Serial No. 105,141.

The objects of the invention are to provide an inexpensive tone arm for talking machines which is neat in appearance, and of simple construction. Another object is to provide a flexible mount for the tone arm, whereby it is free to move laterally and vertically within suitable limits.

The invention consists in the combination and arrangements of parts hereinafter described and claimed.

In the accompanying drawings, which form part of this specification, like numerals refer to like parts wherever they occur.

Figure 1 is a plan view of a tone arm and sound box embodying my invention;

Fig. 2 is a side elevation of the tone arm and sound box shown in Fig. 1;

Fig. 3 is a vertical cross-section of the tone arm taken on the line 3—3 in Fig. 2;

Fig. 4 is a vertical cross-section of the flexible joint for the tone arm taken at right angles to Fig. 3; and

Fig. 5 is a horizontal section through the tone-arm on the line 5—5 in Fig. 3.

The tone arm 6 shown in the drawings carries at its outer extremity a sound box 7 of any suitable construction. The sound box is connected to the tone arm by means of an elbow 8, one branch of which is secured to the end of the tone arm, and in the other branch of which there is inserted the hollow stem 9 of the sound box. A stop 10 on the stem 9 of the sound box engages the stop 11 on the elbow 8 to position the sound box and needle at a suitable inclination to the record.

The tone arm 6 is arranged for easy lateral and vertical movement at its free end

upon which the sound box 7 is mounted. The support for the tone arm is a ring 12, which is pivoted to the top of the fixed walls of the vertical sound passage 13 of the machine by pivot screw 14 so as to permit of vertical movement of the free end of the tone arm. The ring 12 has an internally threaded screw flange 15 within which is a screw ring 16. A ring 17, which is fixed upon the end of the tone arm, is arranged for rotation between the screw ring 16 and flanged ring 12, and thereby the tone arm is free to swing laterally. Ball races are formed in the opposing faces of the flanged ring 12, screw ring 16, and rotatable ring 17, and balls 18 are arranged in these races to reduce the friction between the rotatable ring and the fixed ring. A suitable weight attached to a chain 19 which is secured to the ring 12 balances the weight of the overhanging portion of the tone arm.

The foregoing arrangement is considered only as an example and as the one most generally adapted to the tone arm as shown. Therefore, I do not wish to be limited to the precise forms and arrangements shown in the drawings.

I claim the following as my invention:

1. In a talking machine, a pivot support for the tone arm comprising a ring secured to said tone arm, and oppositely disposed rings surrounding said tone arm, said last mentioned rings being disposed on each side of the ring of said tone arm and being mounted for oscillation upon a horizontal axis.

2. In a talking machine, a pivot support for the tone arm comprising a ring secured to said tone arm, and oppositely disposed rings adjustable with respect to each other and surrounding said tone arm, said last mentioned rings being disposed on each side of the ring of said tone arm and being mounted for oscillation upon a horizontal axis.

3. In combination with the main sound conducting device of a talking machine, a supporting collar sleeved on said sound conducting device, and a tone arm having one end rotatably arranged within said supporting collar, said supporting collar being pivotally secured to said sound conducting device so as to oscillate upon a horizontal axis,

4. In combination with the main sound conducting device of a talking machine, a supporting collar surrounding one end of said sound conducting device, a tone arm 5 having an annular flange at one end thereof rotatably arranged within said supporting collar, and means for holding the flanged end of said tone arm in said supporting collar, said supporting collar being pivotally 10 secured to said sound conducting device so as to oscillate upon a horizontal axis.

5. The combination with the main sound conducting device of a talking machine of a supporting collar loosely securing one end 15 of said sound conducting device, a tone arm having an annular flange at one end thereof loosely arranged within said supporting collar for rotation, and a ring detachably secured to said supporting collar for holding 20 the flanged end of said tone arm in said supporting collar, said supporting collar being secured to said sound conducting device by

means of oppositely disposed pivots so as to oscillate upon a horizontal axis.

6. The combination with the main sound 25 conducting device of a talking machine of a supporting collar having an inwardly projecting annular flange at its bottom, said supporting collar being loosely secured on said sound conducting device, a tone arm 30 having a ring secured to one end thereof and loosely arranged within said supporting collars and adapted to being supported upon the annular flange thereof, and a locking ring adjustably secured to said supporting 35 collar above the tone arm ring, said supporting collar being secured to said sound conducting device by means of oppositely disposed pivots so as to oscillate upon a horizontal axis.

Signed at St. Louis, Missouri, this 18th day of August, 1917.

JAMES F. SMITH.
